RESINOUS DEEP TEXTURED DECORATIVE LAMINATE SHEET

Jack August Willard, Hamilton, Ohio, assignor to Formica Corporation, Cincinnati, Ohio

Filed Dec. 7, 1972, Ser. No. 313,022

Term of patent 14 years

Int. Cl. D25—01

U.S. Cl. D87—3 G

The figure is a top plan view of a resinous deep textured decorative laminate sheet showing my new design, the sheet being of conventional thickness.

I claim:

The ornamental design for a resinous deep textured decorative laminate sheet, substantially as shown.
